US0D1074684S

(12) **United States Design Patent** (10) Patent No.: **US D1,074,684 S**
(45) Date of Patent: ** May 13, 2025

(54) **SOLID-STATE DRIVE**

(71) Applicant: **DapuStor Corporation**, Shenzhen (CN)

(72) Inventor: **Yafei Yang**, Shenzhen (CN)

(73) Assignee: **DapuStor Corporation**, Shenzhen (CN)

(**) Term: **15 Years**

(21) Appl. No.: **29/901,198**

(22) Filed: **Aug. 30, 2023**

(30) **Foreign Application Priority Data**

May 4, 2023 (CN) 202330254439.7

(57) **CLAIM**

The ornamental design for a solid-state drive, as shown and described.

DESCRIPTION

FIG. 1 is a front, right, top, perspective view of a solid-state drive showing my new design;

FIG. 2 is a rear, left, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in the figures illustrate portions of the solid-state drive that form no part of the claimed design.

1 Claim, 8 Drawing Sheets
